Primary Examiner — Richard Edgar*Assistant Examiner* — Katherine E Morris(74) *Attorney, Agent, or Firm* — Knobbe, Martens, Olson & Bear, LLP**CLAIM**

The ornamental design for a bottle, as shown and described.

DESCRIPTION

FIG. 1 is a perspective view of a bottle of our design; FIG. 2 is a front view thereof, the rear view being the same; FIG. 3 is a right side view thereof, the left side view being the same; FIG. 4 is a top view thereof; and, FIG. 5 is a bottom view thereof.

The broken lines in the drawings represent portions of the bottle that form no part of the claimed design.
